Des. 1606

William L. McDowell, of Philadelphia, Pa.
Letters Patent No. 1606, dated June 17, 1862,

Dec. 16 06

The schedule referred to in these Letters Patent and making part of the same.

To all whom it may concern,

Be it known that I, William L. McDowell, of the City of Philadelphia in the State of Pennsylvania, have invented or produced a new and original Design for a Stove; and I do hereby declare that the following is a full and exact description of the same, reference being had to the accompanying drawing, making a part of this Specification, and to the letters of reference marked thereon.

The nature of my invention or production consists in the hereinafter specified ornamental configurations, on raised panels on the sides and front of a Cooking stove which, for identity, I name the "Delight".

The drawing represents a perspective view, showing distinctly the said front, and one of two like sides, of the stove; a.a. being two raised panels, on the front plate, having the ornamented configurations on their respective faces, as represented; and b.b.b, three raised panels, on the side plate, having the ornamented configurations on their respective faces, as represented.

What I claim as new, of my invention, and desire to secure by Letters Patent, is

The raised panels a.a, having the ornamented configurations thereon as described; and the raised panels b.b.b, having the ornamented configurations thereon, as described, as a design for a Stove.

(Witnesses.)
